UNITED STATES PATENT OFFICE.

JOSEPH P. DEVINE, OF BUFFALO, NEW YORK.

DRYING MATERIALS.

Continuation of application Serial No. 124,317, filed July 23, 1926. This application filed May 28, 1927. Serial No. 195,088.

My invention relates to a method and apparatus for drying materials and has particularly in view the drying of porous materials. My method is of general application, and can be utilized in connection with the drying of a wide range of organic and inorganic materials, including high tension cables, telephone cables, wood, meat, hides, ceramics, plaster board, earthenware, briquettes, paper, foundry molds and cores, tobacco, mica sheets and other similar materials. While having its present widest application in connection with the removal of the water from such materials, any other vaporizable material can be equally well removed, such as, the various solvents that are used in manufacturing processes.

I will now describe my process and apparatus, and by way of example, in connection with the drying of wood, it being understood that other materials can be dried by the same type of apparatus and in a similar manner. Wood, after it has been sawed, is stacked and left exposed to the air for a period of several weeks or months. This is usually referred to as "air seasoning", and wood having been so seasoned usually retains a large percentage of moisture. In order to be used for various purposes, the wood should contain a very small percentage of moisture, and to remove the retained moisture the wood is further dried in kilns, the time varying from days to months, depending upon the character and dimensions of the wood, its moisture content and the type of kiln employed. These dry kilns operate in various ways, and I am aware it has been proposed to dry wood in kilns by heating the surrounding air and circulating it around the wood to remove the excess moisture.

Steam has also been similarly used for the same purpose. Wood has also been dried in a vacuum with and without the simultaneous action of heat. In all of these processes, however, the wood dries more rapidly on the outside than in the interior, with the result that the shrinkage is not uniform, and thus stresses result which may cause what is known in the art as, checking, case-hardening, honeycombing and warping, and rendering the wood unfit for many purposes.

My process, however, is directed to the drying of wood and other materials containing water or other vaporizable substance, by means of pressure reduced below atmos-

pheric pressure, hereinafter called "reduced pressure" and surrounded by saturated vapors. By constantly supplying and maintaining a vapor surrounding the material being dried, I prevent the material near the surface from drying out first, as has heretofore been the case, and keep the moisture content of the material near the surface of the wood substantially as high or higher than the interior portion of the wood.

By carrying on my drying operation under reduced pressure, I also reduce the temperature for drying, far below that which is ordinarily employed in the drying of wood or other materials, and by vaporizing water or solvent, other than is contained in the material, being dried, at an extremely low temperature, I provide a carrying medium for the heat units, and thereby shorten the time of drying, and do not depend upon radiation or induction for transferring the heat in an apparatus operating under "reduced pressure."

As the water or solvent vaporizes within the vacuum chamber, the vapors preheat and in their passage through the vacuum apparatus come in contact with the material being dried. As the temperature of the vapors at this point exceed the temperature of the wood, they condense on the surface of the wood which takes up the heat units. When the vapor pressure on the inside of the wood equals or exceeds the vapor tension on the outside, the moisture commences to leave the wood in the form of vapor from the inside out, with the result that the outside of the wood is in a moist condition, until the last percentage of moisture is removed from the outer surface, facilitating the drying of the wood and preventing checking, case-hardening, honeycombing and warping.

Referring to the drawings for a more complete disclosure of the invention:

Fig. 1 is a longitudinal section of a vacuum dryer.

Fig. 2 is a transverse section of Fig. 1.

Fig. 3 is an elevation of an assembly of a vacuum dryer with a barometric condenser and vacuum pump.

Figs. 4 and 5 are elevations of an assembly of a vacuum dryer with a surface condenser and vacuum pump.

The drying retort 1 is formed into a cylindrical or other conventional shape, and can be made of boiler plate or other materials,

and has a door 2 at one or both ends pivotally mounted and supported from the arm 3 or can be hinged or operated by many well known methods. Clamping nuts 4 are employed, in connection with an interposed gasket to keep the door substantially vacuum tight when closed.

Within the retort is a movable platform 5 for supporting the material to be dried, 10 tracks 7 and 8 being supported by the bottom of the retort, and on which the platform may slide in and out.

Running lengthwise and on the inside of the retort are heating elements, comprising 15 separate groups of steam pipes 9, 10, 11 and 12, independently controlled and which serve to heat the contents of the retort and also aid by their location to offset any loss of heat by radiation through the walls of the retort. 20 The effect can be carried out by other means such as a steam jacket or jackets.

The subdivided heating elements have another advantage in permitting various steam pressures to be carried on the different 25 groups of coils in order to maintain an even temperature throughout the apparatus.

In the bottom of the retort is a receptacle or vaporizer 13 provided with a supply pipe 14 for feeding water or other volatile solvent 30 thereto as desired, and a drain pipe 14' for drawing off the water as desired. Located adjacent to the receptacle 13 and in the bottom of the retort are coils of pipes 15 and 16 for supplying heat to the contents of the 35 retort, and particularly to the vaporizing receptacle for causing evaporation of the water or solvent vapors therefrom.

The coils 15 and 16 in the bottom of the retort serve two purposes. It is very difficult 40 to transmit heat inside of a vacuum apparatus, particularly under "reduced pressure." The location of the cluster of coils in the bottom of the retort is most efficient, since the heat from these coils rises, comes in contact with the wood, gives off heat units to the wood and consequently facilitates evaporation or drying. They also serve to evaporate the liquid in the vaporizer. It is apparent, however, that other positions of the coils and 45 vaporizer might be employed than that shown and that other means than coils or a vaporizer could be used as a source of heat.

Extending lengthwise of the retort is a 50 perforated steam spray pipe 17.

Surmounting the retort is a steam dome 55 18, and this may be connected through the medium of a vapor pipe 19 to a conventional barometric condenser 20, provided with an air line separator 21, and tail pipes 22 and 23 leading to a hot well 24, to receive the condensate. Any type of condenser may be employed.

Connected to the condenser by a suitable 60 pipe line 25 is a vacuum pump 26. It will be clear therefore that when the vacuum

pump is in operation, all vapors will be exhausted from the retort 1, and any condensable gases will be collected by the condenser.

In Figures 4 and 5 I have shown in combination with the retort, a surface condenser 27, a receiver 28 for saving the condensate, and a dry vacuum pump 29. A pressure gauge 30 is provided to indicate the amount of vacuum or reduced pressure within the 75 retort, and a valve 31 is also provided to break the vacuum.

Operation.

The wood or other material to be dried is 80 placed in the retort and the door or doors clamped tight. Steam is now admitted to the heating elements 9, 10, 11, 12, 15 and 16, and low pressure steam may be injected into the interior of the retort through the 85 perforated steam spray pipe 17, all for the purpose of preliminarily and rapidly heating up the wood in the retort, care being taken not to subject the wood to an injuriously high temperature.

Water having been already admitted to the receptacle or vaporizer, and heated up, the steam is now shut off from the pipe 17, the vacuum pump is started, the pressure reduced, and this condition maintained for a 90 number of hours depending upon the particular kind of wood or other materials being dried.

Assuming the wood to be first uniformly heated to a temperature less than the boiling 100 point of water at atmospheric pressure, the obtaining and maintaining of a vacuum will reduce the boiling point of the water contained in the wood as well as that in the vaporizer. This will, of course, cause rapid 105 vaporization of the water, and as the vapor is evolved it will be drawn out of the retort by the vacuum pump. As the water in the wood vaporizes, it takes up its latent heat of vaporization from the wood. This causes 110 the wood to drop to a lower temperature than the surrounding saturated vapor with the result that the vapors in the retort will condense on the surface of the wood, imparting to the wood their heat units of condensation. By reason of the continuous 115 vaporization of the water in the vaporizer, there is a continuous supply of heat units to the wood, offsetting thereby the tendency of the wood to drop to a lower temperature 120 from the volatilizing of the water within its pores. It will be clear that so long as there is water in the vaporizer, which is in communication with the vapor in the interior of the retort, the vapor will remain saturated so long as an adequate supply of heat units are transmitted to the vaporizer. It

is clear too that so long as the wood is surrounded by saturated vapor no part of the wood can become any drier than the vapor 125 130

surrounding it. This condition prevents causing uneven stresses in the wood, checking, case-hardening, honeycombing and warping. Prior processes of drying wood have largely depended upon the establishment and maintenance of a moisture gradient to effect the desired result. With that end in view, the wood has first been dried on the outside so that the moisture will flow from the inside to the outside. The effect of drying the wood on the outside, however, has been to close the pores of the wood thereby hindering the escape of vapor from the inside and causing stresses in the wood, with resulting checking and warping, case-hardening and honeycombing. In my process however, there is no uneven drying, the idea being to uniformly reduce the moisture content of the wood by exhausting the formed vapors, the presence of the saturated surrounding vapor acting as a control to prevent uneven drying of any portion of the wood.

After all of the water in the wood has been evaporated, then there remains so much moisture as is contained in the saturated vapor corresponding to the pressure in the retort.

With a vacuum maintained as high as 29", the total amount of liquid in the saturated vapor medium surrounding the wood will be very small. During the drying operation, the temperature of the wood will vary from approximately 160° F. with a 20" vacuum, and a total vapor pressure of about 5 lbs. per square inch, to 60 to 80° F. with approximately a 29" vacuum and a total vapor pressure of approximately 0.5 lbs. per square inch.

Maple shoe lasts have been dried by my process to substantially bone dryness in 68 hours, and to commercial dryness in about 50 hours. The best that could be done with current known processes was 60 to 90 days.

While it may not be necessary to have the vapors entirely saturated as differentiated from vapors of relatively high humidity, still it is an advantage to have only saturated vapors, and in the embodiment of my process herein disclosed, I employ only saturated vapors. Inasmuch as the water is vaporized inside the retort, the boiling point of that water is determined by the "reduced pressure" under which the apparatus is operating.

By creating the vapors inside the retort, they serve not only as the heat carrying medium to the materials being dried, but also prevent harmful stresses occurring in the outer portion of the materials.

This application is a continuation of my application Serial No. 124,317 filed July 23, 1926.

It will be apparent therefore that while I have described my process in connection

with the drying of wood that many other materials can be dried equally well wherever the same problem is presented. Such materials will include those where the pores of the material, contain the liquid which it is desired to eliminate, and wherein other drying methods would cause the outside portions to become dry before the interior.

I am aware that my invention may be embodied in other specific forms without departing from the spirit or essential attributes thereof, and I therefore desire the present embodiment to be considered in all respects as illustrative and not restrictive, 75 rather than to the foregoing description to indicate the scope of the invention.

Having described my invention, what I claim as new and desire to secure by Letters Patent is:

1. The method of drying materials in a closed receptacle by subjecting them to heat under a sustained reduced pressure during the entire drying operation in the presence of a vapor maintained at a relatively high 90 humidity for an extended period of time and removing vapor from the receptacle during the drying operation.

2. The method of drying materials in a closed receptacle by subjecting them to heat 95 under a sustained reduced pressure in the presence of a vapor maintained constantly saturated for an extended period of time and removing vapor from the receptacle during the drying operation.

3. The method of drying materials in a closed receptacle by subjecting them to a sustained reduced pressure for an extended period of time, continuously supplying heat to the materials by means of vapor generated in the receptacle, to vaporize the liquid contained in the materials, maintaining a constantly saturated vapor around the materials during the entire drying operation and continuously removing vapor from the receptacle during the drying operation.

4. The method of drying materials in a closed receptacle by subjecting them to heat under a sustained reduced pressure during the entire drying operation in the presence 115 of a vapor maintained at a relatively high humidity for an extended period of time, continuously supplying heat units by means of vapor to the said materials to offset the lowering temperature from the volatilizing 120 of the liquid in the materials and removing the vapor from the receptacle during the drying operation.

5. The method of drying materials containing water or other vaporizable substance by means of sustained reduced pressure, constantly supplying and maintaining a saturated vapor surrounding the material being dried to prevent the material near the surface from drying out first, vaporizing 130

- water or solvent, other than is contained in the material being dried, at a relatively low temperature to provide a carrying medium for the transfer of heat units to the said materials, and removing the formed vapor from the receptacle during the drying operation.
6. An apparatus for drying materials comprising in combination, a retort, an open vaporizer of liquid in the retort, means for heating the retort to vaporize the liquid in the vaporizer and in the materials, and means for establishing and maintaining a reduced pressure in the retort and for removing the formed vapors from the retort.
7. An apparatus for drying materials comprising in combination, a retort, means for heating the materials in the retort to vaporize the liquid contained therein, means for constantly supplying and maintaining saturated vapor in contact with the said materials, and means for establishing and maintaining a reduced pressure in the retort and for removing the formed vapors from the retort.
8. An apparatus for drying materials comprising in combination a retort, means for constantly supplying saturated vapor to the retort, means for maintaining a supply of heat to vaporize the liquid contained in
- the materials, and means for establishing and maintaining a reduced pressure in the retort and for removing the formed vapors from the retort.
9. An apparatus for drying materials comprising in combination, a retort, means for maintaining a supply of heat to vaporize the liquid contained in the materials, means for constantly supplying saturated vapor to the retort and comprising a body of water or other vaporizing solvent in communication with the interior of said retort, means for vaporizing the said water or solvent, and means for establishing and maintaining reduced pressure in the retort and for removing the formed vapors from the retort.
10. An apparatus for drying materials comprising in combination a retort, means for heating the materials in the retort and comprising a vaporizer, means for supplying heat to the vaporizer, the vapor coming from the vaporizer serving as a heat carrying medium through the materials being dried, and means for establishing and maintaining a reduced pressure in the retort and for removing the formed vapors from the retort.

In testimony whereof I affix my signature.

JOSEPH P. DEVINE.
